Russell G. Livingston, Inglewood, Calif.

Application April 22, 1957, Serial No. 45,835

Term of patent 3½ years

(Cl. D14—3)

Fig. 1

Fig. 2

Fig. 3

The side opposite that shown is identified therewith; the front is substantially plain except for the continuous beads.

The dominant features of my design are shown in full lines in the drawings.

I claim:

The ornamental design for a camping trailer, substantially as shown and described.
